OIL GAUGE ROD WIPER

Raymond J. Davis, Hollandale, Miss.

Application January 2, 1951, Serial No. 203,852

6 Claims. (Cl. 15—210)

1

The present invention relates to new and useful improvements in wipers for the oil gauge rods of motor vehicles and more particularly to a wiper which may be carried in a convenient position on the belt of a service station attendant.

An important object of the invention is to provide a wiper in which a pair of wiper jaws are carried in a container to collect excess oil and handles are provided for the jaws outwardly of the container to close the jaws on a gauge rod and clean the rod by drawing the rod between the jaws.

Another object is to construct the handles and jaws to form a holder for the container.

A further object is to provide an endless wiper pad held on the jaws in stretched U-form and between the open end of which the gauge rod is drawn to clean the rod.

A still further object is to construct wire holding jaws for the pad and on which the pad may be moved to bring clean portions of the pad into wiping position.

Another object is to provide a gauge rod wiper of simple and practical construction which is efficient and reliable in operation, neat and attractive in appearance, relatively inexpensive to manufacture, and otherwise well adapted for the purposes for which the same is intended.

These, together with various ancillary objects and features of the invention which will later become apparent as the following description proceeds, are attained by the device, a preferred embodiment of which has been illustrated by way of example only in the accompanying drawings, wherein:

Figure 1 is a front elevational view;

Figure 2 is a vertical sectional view;

Figure 3 is a vertical sectional view taken on a line 3—3 of Figure 2;

Figure 4 is a top plan view; and

Figure 5 is a perspective view of the united wire jaws and handles.

Referring now to the drawing in detail wherein for the purpose of illustration I have disclosed a preferred embodiment of my invention, the numeral 5 designates a resilient wire frame constructed to provide a pair of jaws 6 and a pair of handles 7.

Each jaw 6 includes a vertical rod 8 having a horizontal arm 9 at its upper end and a short upstanding portion 10 at the outer end of the arm. Each handle 7 also includes a vertical outwardly inclined rod 11 positioned outwardly of an adjacent jaw and with the upper end of the rod 11 united with its companion jaw 6 by a zig-zag connector bar 12 connected to the upper end of

2

the upstanding portion 10 and bar 12 is offset at a point between its ends to form a stop 13.

The lower ends of handles 7 are united by a cross bar 14 which underlies a circular connecting arm 15 which unites the lower ends of jaws 6. One side of circular arm 15 is open and in which a horizontal wiper pad holding bar 16 is centered with one end of the bar 16 soldered or otherwise suitably secured to the circular bar.

An endless wiper pad 17 is constructed of a strip of suitable absorbent material with its ends sewed together as indicated at 18 and the pad is folded to provide inner and outer U-shaped layers 19 and 20 having their upper portions placed over the arms 9 at the upper ends of jaws 6 and having the lower portions of the outer layer 20 placed under the sides of the circular arms 15 and with the lower portion of the inner layer 19 placed under the bar 16, as shown in Figure 2, to thus hold the pad on the jaws.

A tubular container 21 is supported in a vertical position on lower cross bar 14 and in which the jaws 6 and wiper pad 17 are received while the upper edge of the container is positioned outwardly of stops 13, horizontal arms 9 and upstanding portions 10 at the upper ends of the jaws to thus hold the container centered between handles 7.

A clip 22 is secured to the upper end of container 21 for attaching the device to the belt 23 of a person.

In the operation of the device, tension of the jaws 6 normally holds the sides of U-shaped pad 17 separated to receive an oil gauge rod 24 inserted downwardly in container 21 and by squeezing handles 7 the jaws will be closed to bring the sides of the pad into close wiping contact with the rod as it is withdrawn to clean the rod.

The pad may be turned on upper arms 9 and lower circular arm 15 to bring clean portions of the pad into wiping position, when desired.

In view of the foregoing description taken in conjunction with the accompanying drawings it is believed that a clear understanding of the device will be quite apparent to those skilled in this art. A more detailed description is accordingly deemed unnecessary.

It is to be understood, however, that even though there is herein shown and described a preferred embodiment of the invention the same is susceptible to certain changes fully comprehended by the spirit of the invention as herein described and the scope of the appended claims.

Having described the invention, what is claimed as new is:

1. An oil gauge rod wiper comprising a tubular

container, a pair of resilient wire jaws positioned vertically in the container, a pair of vertical wire handles positioned outwardly of the container and united at their upper ends with the jaws for actuating the latter, a wiper pad on the jaws, and a supporting bar underlying the container and united with the lower ends of the handles.

2. An oil gauge rod wiper comprising a pair of vertical resilient wire jaws, upper and lower horizontal arms at the ends of the jaws, a lower horizontal pad holder supported by the lower arms between the lower ends of the jaws, an endless pad including folded inner and outer U-shaped layers supported at their upper portions on said upper arms and with the lower portion of said outer layers underlying the lower arms and the lower portion of said inner layer underlying the lower horizontal pad holder to support the pad on the jaws, a tubular container enclosing the jaws and pad, a pair of vertical wire handles outwardly of the container, a connector uniting the lower ends of the handles and on which the bottom of the container is supported, and connectors uniting the upper ends of the jaws with their adjacent handles and holding the handles in an outwardly inclined position for actuating the jaws by inward pressure on the handles.

3. An oil gauge rod wiper comprising a pair of vertical resilient wire jaws, upper and lower horizontal arms at the ends of the jaws, a lower horizontal pad holder supported by the lower arms between the lower ends of the jaws, an endless pad including folded inner and outer U-shaped layers supported at their upper portions on said upper arms and with the lower portion of said outer layers underlying the lower arms and the lower portion of said inner layer underlying the lower horizontal pad holder to support the pad on the jaws, a tubular container enclosing the jaws and pad, a pair of vertical wire handles outwardly of the container, a connector uniting the lower ends of the handles and on which the bottom of the container is supported, connectors uniting the upper ends of the jaws with their adjacent handles and holding the handles in an outwardly inclined position for actuating the jaws by inward pressure on the handles, and stops on said last-named connectors centering the container on the jaws.

4. An oil gauge rod wiper comprising a tubular container, a wire frame retaining the container in an upright position, said frame including a pair of spaced jaws disposed within and extending longitudinally of said container, handles disposed exteriorly of the container and connected at their upper ends to said jaws for moving them toward one another, and a supporting bar underlying said container and connecting said handles to one another at their lower ends, a wiper pad on said jaws.

5. An oil gauge rod wiper comprising a tubular container, a wire frame retaining the container in an upright position, said frame including a pair of spaced jaws disposed within and extending longitudinally of said container, handles disposed exteriorly of the container and connected at their upper ends to said jaws for moving them toward one another, and a supporting bar underlying said container and connecting said handles to one another at their lower ends, a wiper pad on said jaws, a split ring connecting the lower ends of said jaws to one another within the container, said wiper pad comprising an endless belt having its ends secured to the upper ends of said jaws and its intermediate portion secured to said ring.

6. An oil gauge rod wiper comprising a tubular container, a wire frame retaining the container in an upright position, said frame including a pair of spaced jaws disposed within and extending longitudinally of said container, handles disposed exteriorly of the container and connected at their upper ends to said jaws for moving them toward one another, and a supporting bar underlying said container and connecting said handles to one another at their lower ends, a wiper pad on said jaws, said handles comprising substantially vertical wire portions extending longitudinally along the container.
